CLARENCE F. WILEY, OF TAUNTON, MASSACHUSETTS, ASSIGNOR TO MAGEE FURNACE COMPANY, INC., OF BOSTON, MASSACHUSETTS, A CORPORATION OF MASSACHUSETTS.

COMBINATION COAL AND GAS RANGE.

1,407,715.

Specification of Letters Patent. Patented Feb. 28, 1922.

Application filed July 11, 1918. Serial No. 244,491.

To all whom it may concern:

Be it known that I, CLARENCE F. WILEY, of Taunton, in the county of Bristol and State of Massachusetts, a citizen of the 5 United States, have invented a new and useful Improvement in Combination Coal and Gas Ranges, of which the following is a full, clear, and exact description, reference being had to the accompanying drawings, forming 10 a part of this specification, in explaining its nature.

The present invention relates to an improvement in a range adapted for burning either coal or gas or both simultaneously as 15 occasion may require.

The invention further relates to that type of range in which the main bake oven ordinarily heated by the burning of coal is utilized also when gas is being burned. The invention pertains essentially to the gas-burning attachment or attachments with which 20 the range is fitted.

The essential object of my invention is to provide an efficient and practical range of 25 the above type. In other words, it is among the objects of my invention to provide a gas-heating attachment which will not interfere in any way with the operation of the range when coal is being used, and which 30 will properly and adequately heat the oven when coal is dispensed with and gas is being used, and which gas attachment, also, may be used for purposes of broiling.

The invention involves other various features of constructive detail pertaining to 35 the fitting and operation of the burner and automatic control of the gas, especially to an arrangement whereby a proper circulation or distribution of heated air may be obtained 40 within the oven when the gas burner is in operation in order to obtain proper baking effect, supply air to the burner and prevent the heat from the burner injuring the walls of the oven, together, also, with other details, all of which can best be seen and understood by reference to the drawings, in which—

Figure 1 is a front elevation of a range embodying my invention, such portion there- 50 of only being shown as is necessary to a proper understanding of the invention.

Fig. 2 shows the end of the range in elevation.

Fig. 3 is a section on the line 3—3 of

Fig. 1, the gas burner being shown in operative position. 55

Fig. 4 is the same as Fig. 3 excepting that the burner is shown in its inoperative or out-of-the-way position and certain other parts also being shown in the position assumed by 60 them when the gas-burning attachment is dispensed with and coal is used in the range.

Fig. 5 is a plan of the burner and certain associated parts to which reference will later be made, and 65

Fig. 6 is a plan of the baffle-supporting rack to which special reference will later be made.

Referring to the drawings:—

1 represents the body of the range provided with the usual parts for burning coal, wood or gas. 70

2 represents the oven having at the rear end thereof a back extension 3, the oven, in other words, being made deeper by the 75 amount of the extension than an ordinary oven. The extension 3 is encompassed by no flue space excepting the back flue 4 which extends upwardly in the rear of the extension to connect with the outlet 5 of the range. 80

In the top of the oven there is arranged a flue 6 which extends from the fore part of the oven to the back and there communicates with an opening 7 in the rear wall of the oven leading into the back flue and outlet of 85 the range. This flue at the forward end thereof is provided with openings 7' into it out of the fore part of the chamber of the oven for purposes later to be explained.

Located within the oven is the burner 8 90 which is of the pivot or swing type, the same being mounted whereby it may be turned to assume a downturned operative position within the oven adjacent its bottom or swung into an upturned out-of-the-way position 95 within the extension.

The burner proper consists of pipes or hollow fixtures 9 rectangularly arranged and preferably provided with reinforcing or strengthening ribs or edges 10. 100

Extending from the burner are arms 11 and 12, respectively. Of these arms the arm 11 is a hollow arm through which gas is admitted to the burner. This arm connects with a mixing tube 13 which extends 105 through the side wall of the extension 3 of the oven above the bottom of the extension, and provides one of the trunnions upon

which the burner is mounted to swing. The other arm 12 of the burner is fitted with a turned end 14 which forms the other trunnion for the burner, the same turning with 5 in a bearing 15 located at the rear of the oven above the bottom of the extension 3 opposite the bearing of the mixing tube or trunnion 13.

In point of structure, the burner, its 10 respective arms and trunnions, of which one comprises a mixing chamber, are preferably made of integral construction as shown.

The arrangement and extension of the 15 arms 11 and 12 bearing the burner and the location of the bearings of the respective trunnions are such that the burner may be turned to assume a downturned operative position as shown in Fig. 3 or an upturned out-of-the-way and inoperative position as 20 shown in Fig. 4. When in its downturned operative position the burner will lie in close proximity and substantially parallel with the bottom of the oven with a forward extension to a point about midway the oven, 25 the burner tubes having preferably a lateral extension of about the full width of the oven. When in its downturned or operative position the burner is supported by lugs 16 projecting from the opposite sides of the oven 30 and against which the outturned rib or edge 10 of the burner has bearing.

It will also be observed that the tubes 9 of the burner are provided with ports 18 formed upon the under side thereof and cut 35 at an angle so that the flame issuing from the burner will project at an angle of about 45° in the direction of the bottom of the oven, but owing to the angularity of their projection and the spacing of the burner 40 from the bottom of the oven the flame does not have contact with the bottom of the oven.

When the burner is swung to its upturned inoperative position it will lie slightly off 45 centre and bear against the rear end of the oven, maintaining its position by gravity.

Gas is supplied to the burner through a 50 pipe connection 20 having a vertically-disposed portion 21 at the end of the range and which portion at the bottom end thereof is provided with a pipe connection 22 which makes a tight though swing-joint connection with the end of the mixing tube as shown in Fig. 6.

The burner is turned to and between its 55 downturned and upturned positions by means of a lever 24. To the end of this lever is pivotally secured a link 25 which is pivotally secured to an arm 26 projecting from the side of the mixing tube 13 constituting one of the trunnions supporting the burner. The lever 24 is fulcrumed to turn 60 upon a boss 27 projecting from the end of the stove and to which the lever is secured by a pin 28. The outer end of the lever 65 projects through a slot 29 in a bracket 30 at

the front of the stove. Beyond the bracket the lever is provided with a handle 31 for operating it.

With the parts thus arranged the burner 70 will be thrown into its downturned or operative position by throwing down the handle of the lever, and to its upturned or inoperative position by lifting the handle or end of the lever. The slot 29 is made of ample 75 length to admit of the lever having sufficient play to effect a proper turning of the burner into its respective turned positions and in practice is made of such length that the ends 33 and 34, respectively, of the slot 80 will define, by the engagement of the lever with them, the properly turned positions, respectively, of the burner, excepting when the burner is turned to a position for broiling, to which reference will later be made.

The turning on or shutting off of the gas 85 supplied to the burner is effected by means of a valve 35 located within the section 21 of the gas pipe connection, and which valve is controlled by means of a turn-rod 36. Connection between the rod and valve is 90 effected by means of a loose joint or coupling 37 of ordinary type. The outer end of the rod projects through the bracket 30 at a point laterally adjacent the slot 29 and a little distance below the top end of 95 the slot. The rod 36 is provided with a knob or handle 38 for turning it.

Projecting laterally from the side of the 100 rod 36 is a stud 40. This stud as the rod is turned is adapted to engage one or the other of stops 41, 42, formed upon the front side of the bracket 30. These stops define the opening and closure of the valve 35, the engagement of the stud with the stop 41 defining the open position of the valve, and the 105 stop 42 in closed position. Projecting laterally from the rod 36 at the rear of the bracket is a finger 43. The relative location of the rod 36 and finger 43 upon it to the slot 29 and to the lever 24 and also the length 110 of the finger are such that when the handle of the lever is drawn up to the upper end of the slot 29 with the burner thrown into its inoperative position, the valve 35 will be closed and the finger 43 will have engagement with the side of the lever. The lever will then prevent the valve being turned into an open position as long as the lever 115 remains at the upper end of the slot. When the position of the lever has been changed 120 for moving the burner into its downturned operative position, then the rod 36 may be turned for opening the valve, the finger then being turned to extend across the slot 29.

The advantage of this arrangement is that 125 the gas cannot be turned on as long as the burner is in its inoperative position, and can only be turned on when the lever has been thrown down for turning the burner into its operative position. When the burner is in 130

its operative position and the gas turned on, the finger will then be extending across the slot 29 and the gas may then be turned off. If, however, the gas is not turned off when 5 the burner is thrown up into its inoperative position by the lifting of the lever, the lever will engage the finger and automatically turn off the gas.

When the burner is in operation for the 10 purpose of baking, the article to be cooked is placed within the oven upon an oven rack 45 supported by flanges 46 projecting from the sides of the oven in the usual manner. In order to prevent the heat from the burner 15 rising directly against the article and to assist in disseminating the heat from the burner throughout the oven, a baffle 47 is provided above the burner and between it and the oven rack 45. This baffle forms a part 20 of, or is supported by, a rack 48, which is slid into and out of the oven and supported by flanges 46 on the sides of the oven the same as the oven rack. A sufficient number 25 of flanges on the sides of the oven are provided so that the baffle may be set at different adjusted spaced positions from the burner. Under certain conditions, when certain articles are to be baked, the baffle may be set very close to the burner and the oven rack 30 supporting the article brought down relatively close to the baffle. Under other circumstances changed relative positions of the baffle-supporting rack and oven rack are desirable, all of which are provided for in the 35 arrangement shown. That is, the baffle may be set at any properly adjusted position in relation to the burner; likewise the oven rack supporting the article. The baffle-supporting rack is indicated in detail in Fig. 6 40 where it is seen that the baffle proper is one such as to substantially cover the burner, and the rack is otherwise made perforated throughout so as not to interfere with a proper circulation of heat at the front and 45 sides of the baffle.

In this connection it will be observed that the baffle-supporting rack, as likewise the oven rack, extend back into the oven only to the point where the extension 3 of the oven 50 begins, stops 49 being provided for the racks. A space is accordingly left back of the baffle and oven plate up through the extension 3 of the oven, which is significant in connection with matter now to be referred to.

55 When the burner is in operation for the purpose of baking, air is admitted to the front of the oven at the bottom through an opening 51 in the oven door 52. This opening is controlled by a slide 53. An outlet is 60 provided from the chamber of the oven through the openings 7 into the flue 6 in the top of the oven and thence out through the opening 7 into the back flue and outlet of the range, as before pointed out. The passage 65 through the flue 6 and opening 7 is con-

trolled by a damper 54 having secured to it a curved arm 55 provided with a turned end. The damper is located outside the oven with the arm extending through the opening 7 into the flue 6 and thence down through the 70 bottom of the flue into the chamber of the oven. The arrangement and relationship of the parts are such that the damper will gravitate to a normal open position and will be moved to a closed position by the engagement 75 of the burner with the turned end of the arm 55, when the burner is moved into its upturned or inoperative position, substantially as shown in Fig. 4. That is, the arrangement is such that when the burner 80 is turned down within the oven for purposes of use, the damper will automatically be released to open, and when the burner is turned up into its out-of-the-way position, the damper is automatically closed for making a 85 tight oven, the slide 53 being then closed by hand.

The relative disposition of the respective air inlet and outlet openings together with the disposition of the burner and baffle is 90 such that as the air enters through the inlet opening 51 in the front at the bottom of the oven it will pass to the burner for supplying air thereto and thence proceed beneath the burner and upwardly back of the 95 burner and baffle through the extension 3 of the oven and thence forward to the front of the oven with the effect of creating a circulation of air within the oven which acts to properly disseminate the heat throughout 100 the oven and prevent its localization at any particular point. The entering air as it passes forward beneath the burner along the lower part of the oven will act to draw in with it air in the fore part of the oven, thereby assisting in the circulation of air within the oven. Inasmuch as the entering air passes directly to the burner it will quickly be heated by the flame and its path is such that it will not cool the oven.

110 A further advantage resides in the fact that as the cool air enters the oven it will circulate beneath the burner and prevent any undue application of heat from the burner to the bottom of the oven.

115 With the arrangement above indicated the burner may be used for purposes of broiling as well as baking. When used for broiling the burner will be elevated into an angular position with relation to the bottom of the oven as indicated in Fig. 4. The burner is maintained in this position by means of a latch or finger 58 located inside the bracket 30 upon a pin or stud 59 arranged to turn within the bracket and fitted on the outer side of the bracket with a knob or head 60 by which it may be turned. The pin is located at a point laterally adjacent the slot 29 in the bracket a little distance above the bottom of the slot, and the extension of the 120

125 bottom of the slot, and the extension of the 130

pin is such that when turned into a substantially horizontal position it will cross the slot 29. When so extended the pin will bear against a stop 61 upon the inner face of the bracket. Thus supported and crossing the slot 29 of the bracket, the finger will act as a stop or rest against which the lever 24 may bear when supporting the burner in its angular position suitable for broiling, the weight 10 of the burner acting to hold the lever against the finger. When it is desired to use the burner for purposes of broiling, the finger is simply turned down to cross the slot and the lever then brought down to rest upon it.

15 Having thus fully described my invention, I claim and desire to secure by Letters Patent of the United States:—

1. A combination coal and gas range having an oven, a burner pivotally mounted to 20 turn within the oven and assume either an upturned out-of-the-way position or a downturned operative position, a pipe connection through which gas is supplied to the burner, a valve therein for controlling the supply 25 of gas, a lever for turning the burner within the oven accessible from the front of the range, a turn-rod connecting with said valve accessible from the front of the range for controlling the supply of gas to the burner, 30 and a finger carried by said rod and engaging said lever to prevent the opening of said valve when said burner is in its upturned out-of-the-way position, said finger coordinating, also, with said lever in manner 35 whereby the lever may automatically close said valve when the lever is moved for turning said burner from a downturned to an upturned position.

2. A combination coal and gas range having an oven, a burner pivotally mounted to 40 turn within the oven and assume either an upturned out-of-the-way position or a downturned operative position, a pipe connection through which gas is supplied to the burner, 45 a valve therein for controlling the supply of gas, a lever for turning the burner within the oven accessible from the front of the range, a turn-rod connecting with said valve accessible from the front of the range for 50 controlling the supply of gas to the burner, and means carried by said rod and co-ordinating with said lever whereby said lever may automatically close said valve when 55 said lever is moved for turning said burner from a downturned to an upturned position.

3. A combination coal and gas range having an oven, a burner pivotally mounted to 60 turn within the oven, a pipe connection through which gas is supplied to the burner, a valve therein for controlling the supply of gas, a lever for turning said burner, a bracket located adjacent the front of the range having a slot in it through which said lever extends, a turn-rod connecting with said valve 65 and extending through said bracket whereby

it may be turned from the front of the range for controlling said valve, means whereby the open and closed positions of said valve may be defined, and means carried by said rod to extend crosswise said slot when said valve is occupying an open position and engage said lever when said valve is occupying a closed position.

4. A combination coal and gas range having an oven, a burner pivotally mounted to 75 turn within the oven and assume either an upturned out-of-the-way position or a downturned operative position, a pipe connection through which gas is supplied to the burner, a valve for controlling the supply of gas, a lever for turning the burner within the oven, means for operating said valve, and means whereby said lever may automatically close 80 said valve when said lever is moved for turning said burner from its downturned operative position to its upturned out-of-the-way position.

5. A combination coal and gas range having an oven, a burner pivotally mounted to 85 turn within the oven and assume either an upturned out-of-the-way position or a downturned operative position, a pipe connection through which gas is supplied to the burner, a valve for controlling the supply of gas, a lever for turning the burner within the oven, 90 means for operating said valve, and means whereby said lever may automatically close said valve when said lever is moved for turning said burner from its downturned operative position, to its upturned out-of-the-way 95 position and whereby, also, said lever will prevent the opening of said valve when said burner is occupying its upturned out-of-the-way position.

6. A combination coal and gas range having an oven provided with an inlet for air at 100 one end of the oven adjacent the bottom thereof and an outlet in the top of the oven at the same end thereof as said air inlet, a burner arranged in the path of the air entering said oven, means whereby fuel may 105 be supplied to the burner, and a baffle arranged within the oven and spaced from the bottom and end walls thereof whereby air entering the oven and heated by said burner 110 may be directed to pass along the bottom of the oven and thence upwardly around said baffle.

7. A combination coal and gas range having an oven provided with an inlet for air at 115 one end of the oven adjacent the bottom thereof, and an outlet in the top of the oven at the same end thereof as said air inlet, a burner located in the bottom of the oven in the path of air entering said oven, means whereby gas may be 120 supplied to the burner, and a baffle arranged within the oven above said burner and spaced from the end walls of the oven whereby air entering the oven and heated by said burner 125 130

may be directed to pass beneath said baffle along the bottom of the oven and thence upwardly around said baffle.

8. A combination coal and gas range having an oven provided with an inlet for air at the front of the oven adjacent the bottom thereof and an outlet at the top front end of the oven, a burner located in the bottom of the oven in the path of air entering said oven whereby the entering air may be heated thereby, means whereby gas may be supplied to the burner, and a baffle arranged within the oven above said burner and spaced from the bottom and rear walls of the oven whereby air entering the oven and heated by said burner may be directed to pass beneath said baffle along the bottom of the oven and thence upwardly around the rear end of said baffle.

9. A combination coal and gas range having an oven, a burner pivotally mounted to turn within the oven and assume an upturned out-of-the-way position at the rear of the oven or a downturned operative position adjacent to and spaced from the bottom of the oven, said burner being also spaced from the front and rear walls of the oven when occupying its downturned position as aforesaid, a baffle disposed within the oven above said burner and spaced from the front and rear walls of the oven, said oven having an air inlet and outlet openings therefrom, the air inlet being formed at the front of the oven adjacent the bottom thereof and the outlet at the top front end of the oven.

10. A combination coal and gas range having an oven, a burner pivotally mounted to turn within the oven and assume an up-

turned out-of-the-way position at the rear of the oven or a downturned operative position adjacent to and spaced from the bottom of the oven, said burner extending transversely the oven, spaced from the front and rear walls thereof when occupying its operative position as aforesaid, said burner having also ports on the under side thereof whereby flame issuing from the burner will be projected in the general direction of the bottom of the oven when the burner is in operation, a baffle disposed above said burner and spaced from the front and rear walls of the oven, said oven having an air inlet and outlet openings therefrom, the air inlet being formed at the front of the oven adjacent the bottom thereof and the outlet at the top front end of the oven.

11. A combination coal and gas range having an oven, a burner pivotally mounted to turn within the oven and assume either an upturned out-of-the-way position within the back of the oven, a partially downturned angular position within the chamber of the oven and a further downturned position adjacent the bottom of the oven, a lever for turning said burner arranged adjacent the end of the range, means connecting the lever with said burner, a bracket arranged adjacent the front of the range having a slot in it through which said lever extends, and a manually-controlled stop mounted upon said bracket with which said lever is adapted to have engagement for maintaining said burner in its partially downturned angular position as aforesaid.

CLARENCE F. WILEY.
